UNITED STATES PATENT OFFICE.

EDWARD WYLDE AND CHARLES A. REINERS, OF NEW YORK, N. Y., ASSIGNEES TO
ELEVATOR SUPPLY & REPAIR COMPANY, A CORPORATION OF ILLINOIS.

CONTROLLING DEVICE FOR ELEVATOR-CARS AND THE LIKE.

1,317,062.

Specification of Letters Patent. Patented Sept. 23, 1919.

Application filed September 12, 1914. Serial No. 381,440.

To all whom it may concern:

Be it known that we, EDWARD WYLDE and CHARLES A. REINERS, citizens of the United States, residing at New York city, New

5 York, have invented certain new and useful Improvements in Controlling Devices for Elevator-Cars and the like, of which the following is a clear, full, and exact description.

10 Our invention relates to a device for controlling the operation of a motor operating a traveling car, and our object is to prevent the operator from running the car at too great a speed during a part of the travel of 15 the car.

In elevator systems installed in large buildings some of the bank of elevators usually run "express" for a part of the distance. In a thirty story building for example, some 20 of the cars will make no stop to the fifteenth floor and then continue as local cars from there to the top of the building. In order that the car shall run at high speed, say at the rate of 900 feet a minute, to the first 25 stop, a motor of relatively large power is usually provided. But as the operator may have to stop at each floor from the first local stop, it is undesirable to have the complete high speed power of the motor under the 30 control of the operator after he leaves the first local stop, because the frequent starting and stopping of the car would waste power and would often start the car at too great a speed to be easily controlled for the local 35 stops. It is therefore desirable to provide a construction by which a suitable speed-reducing means shall be introduced automatically at or about the first local stop so that from there to the top of the building and 40 back again, the operator cannot run his car at a speed as great as the car runs during the "express" travel.

In the preferred embodiment of our invention shown in the drawings,

45 Figure 1 is a diagram showing my invention as applied to an elevator car operated by an electric motor; and

Figs. 2 and 3 are modifications.

1 represents the car with a cable 1* passing over a sheave 2 and attached to a counter-weight 3. The motor 4 is in this case an electric motor which may be direct-connected to the sheave as is usual. 32 is the usual controller in the car by which the elevator 55 may be operated and its speed controlled in

the ordinary manner. 5 is a speed-reducing means for the motor, which in the present case is an ohmic resistance.

Assuming that the car is traveling upward and has not yet reached the floor at which the car becomes a "local", the circuit is then through the controller 32, motor 4, contact 22, switch 7, contact 25 and back to the source of supply. The switch 7, if thrown across to contact with block 24, will cut in 65 the resistance 5 and consequently reduce the speed at which the motor may be run, and if the switch is so thrown at or about the first local stop, the operator cannot thereafter run the car at the "express" speed but 70 only at a reduced speed. If the switch is thrown back to the position shown when the car on its down trip again reaches the first local stop, the resistance will be cut out and the operator may then run his car at the 75 "express" speed again for the rest of the downward travel.

Various means may be provided for automatically throwing the switch at the points desired. In Fig. 1 we have diagrammatically shown a construction by which this may be done by a simple addition to the signal system now widely in use and shown for example in the Smalley and Reiners Patent #634,220. 8 and 9 are magnets for throwing the switch from one side to the other. 10 and 11 are stationary contact strips, and 14 and 15 are moving brushes traveling along the same and which make contact at suitable times with the fixed contacts 12 and 13. 18 is a circuit-shifting switch thrown by the car as it reverses its direction of travel. Assume now that the fifteenth floor is the point at which the car becomes a local and that the fixed contact 13 is so positioned that 90 brush 15 will strike it when the car reaches the fifteenth floor, the circuit will then be closed from the battery 19 through switch 18, contacts 17 and 11, brush 15, contact 13, magnet 9 and back to the battery. This will 100 energize magnet 9 and throw the switch 7 across to the contact 24 which will then cut in the resistance 5. The operator then cannot run his car except at the reduced speed. When the car reaches the top of the shaft 105 and reverses its direction of travel, the switch 18 will be thrown across to contact 16. The brushes 13 and 14 are then in the dotted line position we will assume. When the car reaches the fifteenth floor or thereabout in 110

its downward travel, brush 14 will contact with block 12 and energize magnet 8, throwing switch 7 back again to the position shown and cutting out the resistance 5. Such an arrangement automatically prevents the operator from running his car at a too great speed during the "local" travel of his car. The points at which the switch 7 will be thrown may be determined by suitably placing the contacts 12 and 13. They need not be placed so as to throw the switch at exactly the same points during the travel of the car. One of them is shown slightly in advance of the other. At 6 we have shown a conventional representation of suitable adjusting means for the resistance 5 so that the local car speed can be cut down to any extent desired.

In Fig. 2 we have shown a slightly different construction for operating the switch 7. In this figure the resistance 5 is cut in and out by a weighted switch 7* operated by a magnet 23. The switch arm 20 is moved in the direction indicated by the arrow while the car is moving up and strikes segment 21 at the point where the resistance is desired to be cut in.

In Fig. 3 we provide a pivoted switch arm 7* provided with a spring-pressed toggle 27, 28 which can be thrown in any manner desired, for example by a moving part (not shown) which will contact with the tail 31 and throw the switch at the points desired.

We are aware that our invention may be adapted to various installations and types of motors and may be widely varied without departing from the scope of our invention, and we therefore do not desire to be limited to the constructions illustrated.

40 What we claim is:—

1. In combination with an elevator car, the path of travel of which comprises an express zone and a local zone, an operating motor for said car, and means under control of an operator on said car for starting and stopping said car at selected points in the local zone, and for varying the speed of the motor throughout the path of travel of said car, of means for reducing the maximum speed limit of the motor, and automatic means for maintaining said speed reducing means in operative relation to said motor while the car is in the local zone and for maintaining said speed reducing means out of operative relation to said motor while said car is in the express zone.
2. In combination with an elevator car,

an operating motor for said car, means under control of an operator on said car for stopping and starting said car at selected predetermined points in its path of travel, means for reducing the maximum speed of said motor, and automatic means controlled by the car at one of said predetermined points for rendering said speed reducing means effective whenever the car is between certain of said points, and for rendering said speed reducing means ineffective when the car is between other points.

3. The combination with an elevator car, the path of travel of which comprises an express zone and a local zone, an operating motor for said car, a controller on said car, conductors for connecting said motor and controller in circuit, said conductors including two members of different resistances, a switch associated with said members, an electromagnet arranged to operate said switch to close said circuit through one of said members, a second electromagnet arranged to operate said switch to close said circuit through the other of said members, a source of current for energizing said electromagnets, and means operating synchronously with said car for connecting one of said magnets to said source of current when the car passes from its express zone to its local zone and for connecting the other electromagnet to said source of current when said car passes from its local zone to its express zone.

4. In combination with an elevator car, the path of travel of which comprises an express zone and a local zone, an operating motor for said car and means under control of an operator on said car for starting and stopping said car at selected points in the local zone and for varying the speed of the motor throughout the path of travel of said car; of means rendered effective as an incident to the passage of the car into the local zone for limiting the speed of the motor as controlled by the operator while the car is in the local zone, said means being rendered ineffective as an incident to the car again passing into the express zone.

Signed at 105 W. 40 St., New York, N. Y., this 10th day of Sept. 1914.

EDWARD WYLDE.
CHARLES A. REINERS.
